VALVE ACTUATING LEVER

Herman E. Pleasant, Holland, Mich., assignor to
 Crampton Manufacturing Company, Holland,
 Mich., a corporation of Michigan

Application September 1, 1943, Serial No. 500,752

1 Claim. (Cl. 4—67)

The present invention relates to valve actuating levers and more particularly to improvements in handle and valve operating lever assemblies especially adapted for use in connection with flushing tanks.

The primary objects of the instant invention are to provide an assembly of the general character above indicated which has relatively few parts; to provide such an assembly which is simple yet sturdy in construction; to provide such an assembly which is compact and efficient in use; to provide such an assembly which may be readily and conveniently affixed on the wall of a flushing tank; and, to provide such an assembly which is reasonably economical in manufacture.

The device herein illustrated and described is a modification of or improvement over the device shown and described in United States Letters Patent No. 2,295,686 for "Valve actuating lever," filed November 21, 1941, by myself and Fred M. Keller, issued September 15, 1942.

An illustrative embodiment of the invention is shown in the accompanying drawing, wherein—

Figure 1 is a fragmentary front elevational view of a flushing tank, partly broken away and showing a conventional ball valve device operatively connected with its actuating lever assembly;

Figure 2 is an enlarged sectional view thereof on line 2—2 of Figure 1;

Figure 3 is an enlarged side elevational view of the handle of the assembly, a portion thereof being broken away on line 3—3 of Figure 4;

Figure 4 is a bottom plan view of the handle;

Figure 5 is an enlarged side elevational view of the handle and a fragmentary portion of the operating lever shown in its assembled relation with the wall of the flushing tank;

Figure 6 is a sectional view on line 6—6 of Figure 2; and

Figure 7 is a sectional view on lines 7—7 of Figures 2 and 5.

Referring then to the drawing wherein like parts of the assembly shown are each designated by the same numeral in the several views, a flushing tank 10 of conventional type and having an outlet 11, is provided with an overflow pipe 12 connected with the outlet port below the valve seat 13, all as best shown in Figure 1.

A ball valve 14 disposed upon its seat 13 as shown in full lines in Figure 1 is elevated therefrom to its position shown in dotted lines in the same view when the tank is flushed by means of the actuating lever 15 through a pair of articu-

lated links 16, 17, the upper of which is pivotally connected at one end of the actuating lever 15 and the lower of which is rigidly secured to the ball valve 14 and which lower link 17 is vertically slidably embraced within aligned vertical apertures in the fingers 18 of the bifurcated bracket 19 secured to the overflow pipe 12 in a lateral disposition relative thereto.

The front wall of the flushing tank 10 is provided with an opening 20 therethrough, preferably squared or otherwise non-circular in character, and a tubular fixture 21 projected through the opening 20 of the tank 10 and having a circular head 22 has an externally threaded shank 23, an intermediate squared portion 24 embraced within the squared opening 20 of the tank 10 and spaced axially projecting shank end fingers 25 forming a non-circular opening at the end of the tubular shank 23 of the fixture 21.

A nut 26 threaded on the shank 23 of the fixture 21 is preferably employed to secure the fixture in its assembled relation with the wall of the flushing tank 10.

A handle 27 provided with a laterally turned head 28 having a chambered recess 29 therein within which recess the circular head 22 of the fixture 21 is adapted to seat, is provided with a non-circular spindle 30, cruciform in cross section for a portion of its length to provide strength and projecting through the tubular shank 23 of the fixture 21 and beyond the ends of the spaced axially projecting shank end fingers 25.

The actuating lever 15 has a laterally turned portion 31 having a spindle end receiving aperture 32 and provided with a bifurcated head 33 adapted to be spacedly seated between the spaced axially projecting shank end fingers 25 and in secured relation to the end of the spindle 30, the actuating lever 15 having a rotative movement with respect to the fixture 21 limited by the engagement of its bifurcated head between the spaced fingers 25 as best shown in Figure 7.

In assembly of the device in operative position with respect to the flushing tank 10 and as shown in Figure 1, the actuating lever of the assembled fixture is inserted from the front of the tank through its squared opening 20 with the squared portion 24 of the fixture 21 embraced by the squared wall of the opening in the tank whereupon the nut 26 is threaded on the shank 23 of the fixture and drawn up tight against the inner wall of the tank as best shown in Figures 2 and 5.

It will thus be seen that tilting of the handle 27 from its position shown in full lines in Figure 5 to its position shown in dotted lines in the

same view lifts the ball valve 14 from its seat 13 resulting in flushing of the tank since the rotation of the handle 27 within the fixture 21 is limited by its non-circular spindle 30 in engagement with the spaced shank end fingers 25 of the fixture 21.

While but one specific embodiment of the invention has been herein shown and described, it will be understood that certain details of the construction shown may be altered or omitted without departing from the spirit of the invention as the same is defined by the following claim.

I claim:

In a device of the class described: a tubular fixture adapted to be fixedly secured through the wall of a tank, said fixture having a flanged head

provided with a screw-threaded shank having spaced axially projecting shank end fingers; a handle provided with a laterally turned head having a chambered recess within which the flanged head of the fixture is seated, said laterally turned head having a spindle with its terminal portion located between said axially projecting end fingers in spaced relation with the same and projected through the fixture beyond the ends of the spaced axially projecting fingers; and an actuating lever having a laterally turned portion secured to the end of the spindle having a bifurcated head spacedly seated between said axially projecting fingers providing a limited rotative movement between said fixture and lever.

HERMAN E. PLEASANT.
